UNITED STATES PATENT OFFICE.

JOHN ALBRECHT, OF MASSILLON, OHIO.

COMBINED RAIL CHAIR AND TIE.

SPECIFICATION forming part of Letters Patent No. 546,800, dated September 24, 1895.

Application filed May 1, 1895. Serial No. 547,745. (No model.)

To all whom it may concern:

Be it known that I, JOHN ALBRECHT, a citizen of the United States, residing at Massillon, in the county of Stark and State of Ohio, have invented certain new and useful Improvements in a Combined Rail Chair and Tie; and I do hereby declare that the following is a full, clear, and exact description of the same, reference being had to the annexed drawings, making a part of this specification, and to the letters of reference marked thereon, in which—

Figure 1 is a longitudinal section of the tie, showing the rail-locking dogs placed in proper position, also showing a transverse section of the railway-rails. Fig. 2 is an end view of the railway-tie, showing an edge view of one of the locking-dogs, also showing a railway-rail placed in proper position upon the tie. Fig. 3 is a detached view of one of the rail-locking dogs. Fig. 4 is a view showing a portion of the bottom plate of the tie. Fig. 5 is a detached view of the locking key or wedge. Fig. 6 is a view showing a portion of the tie and illustrating one of the openings for inserting the locking-dogs.

The present invention has relation to a combined rail chair and tie; and it consists in the different parts and combination of parts hereinafter described, and particularly pointed out in the claims.

Similar letters of reference indicate corresponding parts in all of the figures of the drawings.

In the accompanying drawings, A represents the top or upper section of the tie proper, which is substantially of the form shown in Figs. 2 and 6, and, as shown, said section consists of a channel-bar formed of proper size and strength to produce a tie to properly support and hold the railway-rails, and for the purpose of forming a base of sufficient width the sides of the section A are flared, substantially as illustrated in the drawings; but it will be understood that the sides may be formed at right angles to the top and bottom of the tie proper without departing from the nature of my invention. The bottom or lower portions of the sides of the section A are provided with the flanges *a*, which flanges are for the purpose of providing a means for properly securing the bottom or base B to the section

or portion A by means of suitable rivets or their equivalents. The bottom B is provided with the longitudinal groove *b*, which groove 55 may be formed throughout the entire length of the bottom plate B.

The locking-dogs C are substantially of the form shown, and, as shown, they are provided with the curved portions *c*, which curved portions are for the purpose of properly abutting against the inner faces of the railway-rails *d*.

The locking-dogs D are formed substantially as illustrated in the drawings, and, as shown, they are provided with the curved portions *e*, said curved portions being so arranged that they will properly abut against the outer faces of the railway-rails.

The bottom or lower ends of the dogs C and D are each provided with the ribs *f*, which 70 ribs are entered or seated in the groove *b*, said ribs and groove being for the purpose of securely holding the dogs C and D against lateral displacement.

The top or upper portion of the section A is 75 provided with the openings *g*, which openings are for the purpose of providing a means for properly entering the locking-dogs C and D.

For the purpose of preventing any upward movement of the locking-dogs after they have 80 been placed in proper position the openings *g* are provided with the narrowed portions *g'*, into which narrowed portions the dogs are slipped, so as to properly engage the shoulders *g''* on the dogs C under the top of the section A.

For the purpose of securely locking or binding the dogs C and D the keys or wedges E are provided, which keys or wedges are placed in the position illustrated in Fig. 1. For the 90 purpose of preventing any accidental displacement of the keys or wedges E the sides of said keys or wedges are roughened or slightly serrated, as illustrated in the drawings.

Having fully described my invention, what 95 I claim as new, and desire to secure by Letters Patent, is—

1. The combination of the section A, having secured to the bottom or lower portion of said section the plate B, provided with the groove 100 *b*, the locking dogs C and D, provided with the ribs *f*, and the keys or wedges E, substantially as and for the purpose specified.

2. The combination of a hollow tie provided

with a grooved bottom, the locking dogs provided with ribs upon their bottom or lower ends, and the serrated keys or wedges, substantially as and for the purpose specified.

5 3. In a railway tie the section A, provided with flaring sides, the grooved bottom B, secured to the section A, the locking dogs having ribs formed upon their bottom or lower ends, and means for securing said locking

dogs, substantially as and for the purpose so specified.

In testimony that I claim the above I have hereunto subscribed my name in the presence of two witnesses.

JOHN ALBRECHT.
